DES. 2070

Letters Patent No. 2070-Dated May 16-1865.

Design for a Coffin.

The schedule referred to in these Letters Patent and making part of the same.

To all whom it may concern:

Be it known that we, G. W. and M. P. Woolley, of the City and County of Hartford and State of Connecticut have invented or produced a new and original Design for Burial Basket, and we do hereby declare that the same is described in the accompanying specification and photographic view, in which the same letters indicate like parts.

In the accompanying photographic view, are shown a new and original design for a burial basket.

A and A, are plain sides and ends configurated with ornamental moulding. B. Case flattened corners. Distinct lid proper, having a raised panel E, surrounded with a plain or moulding F, and having double panels configurated with ornamental moulding G, the whole combined to produce a rich and ornamental design for a burial basket.

What we claim, therefore, and desire to secure by Letters Patent is

The design as herein illustrated and described for a Burial basket.

Witnesses,

Eli Lennox,
